[57] **CLAIM**

The ornamental design for an aerobic exerciser for the upper body, as shown and described.

DESCRIPTION

FIG. 1 is a perspective view of an aerobic exerciser for the upper body showing my design;

FIG. 2 is a reduced front elevational view;

FIG. 3 is a top plan view;

FIG. 4 is a side elevational view;

FIG. 5 is a rear elevational view;

FIG. 6 is a bottom plan view; and,

FIG. 7 is a front elevational view.

The broken line portions of the drawings are for illustrative purposes only and form no part of the claimed design.
